OR THE LIKE

Constance H. Amburgh, Chicago, Ill.

Application September 24, 1956, Serial No. 43,047

Term of patent 7 years

(Cl. D1—8)

Fig. 1.

Fig. 2.

Fig. 3.

Fig. 1 is a front elevational view of an identification label for luggage or the like embodying my new design, the rear portion being substantially plain;

Fig. 2 is a top view of the identification label for luggage or the like shown in Fig. 1, and

Fig. 3 is a sectional view on line 3—3 of Fig. 1.

The dominant features of my design reside in the full line portions of the drawing.

I claim:

The ornamental design for an identification label for luggage or the like, as shown and described.
